(57) **CLAIM**

The ornamental design for a shelving, as shown and described.

DESCRIPTION

FIG. 1 is a first perspective view of a shelving showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the shelving thereof;

FIG. 10 is another perspective view, with the shelving shown in a collapsed configuration thereof; and,

FIG. 11 is an enlarged view of the selected portion 11 in FIG. 1.

The broken lines in FIGS. 1 and 11 represents the bounds of the enlargement taken from FIG. 1 and forms no part of the claimed design. The remaining broken lines shown in the drawings depict portions of the shelving that form no part of the claimed design.

1 Claim, 11 Drawing Sheets
